UNITED STATES PATENT OFFICE.

LAURENCE J. McDONALD, OF PHILADELPHIA, PENNSYLVANIA, ASSIGNOR
TO JOHN C. GRAHAM, OF SAME PLACE.

DESIGN FOR FRINGE.

SPECIFICATION forming part of Design No. 13,275, dated August 29, 1882.

Application filed June 10, 1882. Term of patent 14 years.

To all whom it may concern:

Be it known that I, LAURENCE J. McDONALD, of the city and county of Philadelphia, in the State of Pennsylvania, have invented and produced a new and original Design for Fringe, of which design the following is a specification.

The accompanying drawing is a side view of a section of fringe embodying and illustrating my design, which consists in a fringe having a heading, A, to which is attached a series of pendants, B, of substantially cylindrical contour, each composed of chenille threads twisted helically about the axis of the pendant and projecting loosely therefrom. The pendants are

ornamented by a series of continuous helical stripes, b, formed by the use of warp-threads of two or more different co'ors.

I claim—

A design for fringe, consisting of a heading and a series of chenille pendants of substantially uniform diameter, ornamented by continuous helical stripes, substantially as shown and set forth.

LAURENCE J. McDONALD.
